UNITED STATES PATENT OFFICE.

CARL O. WOLD, OF MINNEAPOLIS, MINNESOTA.

GRADING-MACHINE.

1,023,057.

Specification of Letters Patent.

Patented Apr. 9, 1912.

Application filed May 22, 1911. Serial No. 628,752.

To all whom it may concern:

Be it known that I, CARL O. WOLD, of Minneapolis, Hennepin county, Minnesota, have invented certain new and useful Im-
5 provements in Grading-Machines, of which the following is a specification.

My invention relates to road graders and is designed as an improvement over a machine for similar purposes shown and de-
10 scribed in Letters Patent No. 918,633, issued to me April 20, 1909.

The object of the invention is to simplify and improve the mechanism for raising or lowering the frame of the machine and
15 tilting the scraper blade.

The invention consists generally in a frame, a scraper blade secured thereto, rear-
wardly extending bars pivoted on said frame, crank axles pivoted in said bars and
20 having carrying wheels, and operating levers pivoted on said bars and having toggle connec-
tions with said crank axles.

In the accompanying drawings forming part of this specification, Figure 1 is a per-
25 spective view of a road grading machine embodying my invention, Figs. 2 and 3 are detail views showing the different positions of the toggle mechanism, Fig. 4 is a rear view of the same, Fig. 5 is a detail view
30 showing the construction of the carrying wheels.

In the drawing, 2 represents the forward axle, having a draft pole 3 and carrying wheels 4. These wheels are made of angle
35 bars bent into a circular form, the flanges of the bars forming cutting edges 5 which dig into the soil and prevent slippage sidewise of the machine. The ends of the angle bars are secured together in a suitable manner,
40 as by welding, and the wheels made in this way are much more substantial and durable than when made from cast metal.

6 is a draw-bar pivotally connected at 7 with the steering pole and having a driver's
45 seat 8 at its rear end. Intermediate to the ends of the draw-bar is a frame whereon the scraper blade is mounted. This frame consists, preferably, of side bars 9 having offsets 10 therein, joined together at their for-
50 ward ends by a cross bar 11 that is capable of adjustment longitudinally on the draw-
bar by means of a pin passing through holes in the bar 11 and similar holes 13 in a plate
14 that passes under the draw-bar and has
55 its ends secured to the bars 9. The draw-

bar, the bars 9 and the bar 11 are all pref-
erably constructed of channel bar metal to provide for a maximum of strength and
rigidity with a minimum of weight. The rear ends of the bars 9 are connected by a
60 cross bar 15, also, preferably of channel bar
material, and to this cross bar 15 the for-
ward ends of rearwardly extending brackets
16 are pivoted on pivots 17 which are
mounted in the bar 15 and in straps 18
65 which are secured to the end portions of a
scraper blade 19 that is disposed, preferably,
beneath the offsets 10 and has its upper edge
secured to the bars 9 by suitable means at
a point 20. A bar 16' connects the rear end
70 of the draw-bar 6 with one of the brackets
16, for the purpose of holding said brackets
and the axles journaled therein in proper
relation with respect to the scraper blade
and the draw-bar.

Crank axles 21 are pivoted in bearings in
the brackets 16 and have carrying wheels
22. The rear ends of these brackets are
connected with one another for simulta-
neous movement by a strap 23, so that lat-
eral oscillation of one bracket will cause a
similar movement of the other one. Upon
these brackets quadrants 24 are mounted
and levers 25 have their lower ends pivoted
on these brackets and are provided with
locking latches 26 which engage the quad-
rants 24. Links 26' are pivotally connected
at their upper ends to the levers 25 and at
their lower ends to the crank axles near the
hubs of the carrying wheels, said levers hav-
ing a series of holes 27 at their inner upper
ends to allow for adjustment with respect
to the levers 25. These levers and links
form in effect a toggle joint, the forward
movement of the levers lowering the frame
of the machine and the edge of the scraper,
as shown in Fig. 2, and the backward move-
ment of the levers raising the frame and
scraper, as shown in Fig. 3; and it is evi-
dent that, as the links 26' approach the piv-
otal connection of the levers with the brack-
ets 16, that the power of the levers will be
increased and as the links swing backwardly
from these pivotal points the leverage will
be decreased. I am thus able to utilize the
increase in leverage to handle the scraper
at a point in the operation of the machine
where the maximum of leverage is desired.
The leverage described also allows for the
fine adjustment of the scraper to regulate
75

- the depth of the furrow when the machine is in operation. The adjustment is also rapid, as the levers can be quickly unlocked and thrown from one position to the other 5 and one lever may be operated independently of the other, so that one end of the scraper may be raised or lowered by the movement of one lever without changing the position of the other lever.
- 10 Whenever desired, the position of the scraper with respect to the draw-bar can be changed to obtain the desired angle of the scraper with respect to the work. This adjustment of the scraper blade forms, however, 15 the subject-matter of my Letters Patent above referred to and I make no claim to the same herein. The manner of mounting the brackets on the frame and the form of brackets may be modified, and the connections between the levers and the crank axles may be varied and still be within the scope of my invention.
- I claim as my invention:—
1. In a grading machine, a frame, a scraper blade carried thereby, brackets projecting rearwardly from said frame, crank axles journaled in said brackets and having carrying wheels, levers pivoted on said brackets, rigid links pivotally connected at 25 their upper ends to said levers and at their lower ends to said crank axles, the forward movement of said levers moving said links substantially into alinement with said levers and increasing the leverage thereof on 30 said crank axles, and the backward movement of said levers moving said links away from the pivots of said levers and decreasing the leverage on said crank axles.
  2. In a grading machine, a draw-bar, a frame mounted thereon and comprising end bars and cross bars between them, one of 35 said cross bars having a series of holes therein, a plate also having a series of holes beneath said cross bar, a pin fitting within 40 the holes in said cross bar and plate, and a
  3. In a grading machine, a frame, a scraper blade carried thereby, rearwardly projecting brackets, crank axles journaled in the lower portions of said brackets, levers pivoted in the upper portions of said brackets near the rear ends thereof, said crank axles extending rearwardly to a point beneath said levers, carrying wheels mounted on said crank axles, and links pivotally connecting the rear portions of said crank axles with said levers. 50
  4. The combination, with a frame, of a scraper blade, rearwardly projecting brackets, crank axles journaled in the lower middle portions of said brackets, carrying wheels mounted on the rear ends of said axles, levers pivoted on the upper rear portions of said brackets and having quadrants 55 and locking latches therefor, links having their lower ends journaled on the rear ends of said axles and their upper ends adjustably attached to said levers above the pivots of said levers on said brackets. 60
  5. In a grading machine, the combination, with a frame and draw-bar and a scraper blade and rearwardly projecting brackets, of crank axles having carrying wheels, levers pivoted on said brackets, 75 rigid links connecting said levers with said axles and forming a toggle mechanism, the power of said levers increasing and the movement of said links decreasing with the movement of said levers in one direction, and the movement of said links increasing and the power of said levers decreasing with the movement of said levers in the opposite direction. 80

In witness whereof, I have hereunto set my hand this 10th day of May 1911.

CARL O. WOLD.
